COMBINATION DESK SET AND PAPER WEIGHT, COMPRISING A RULER, LETTER OPENER, AND CIGARETTE LIGHTER

Arthur Salm, Chicago, Ill., and Willi Spitzer, Solingen,
West Germany, assignors to Arthur Salm Inc., Chicago,
Ill., a corporation of Illinois

Application March 17, 1955, Serial No. 35,086

Term of patent 14 years

(Cl. D52—1)

Figure 1 is a perspective view of a combination desk set and paper weight, comprising a ruler, letter opener, and cigarette lighter, showing our new design, the various parts thereof being in closed condition;

Figure 2 is a perspective view of the letter opener contained inside the desk set shown in Figure 1, and forming one handle of said desk set;

Figure 3 is a perspective view of the cigarette lighter in open position forming the handle of our desk set opposite the handle formed by the letter opener;

Figure 4 is a side view of the desk set in closed position;

Figure 5 is a bottom view of the same;

Figure 6 is a top view of the letter opener shown in Figure 2;

Figure 7 is an end view of the desk set; and

Figure 8 is an enlarged cross-sectional view taken on line 8-8 of Figure 2 through the letter opener only.

Our design for a combination desk set and paper weight comprising a ruler, letter opener and cigarette lighter

or the like is particularly characterized by (1) the unity of design of the caps on the letter opener, the lighter, and the closed assembly of both in the ruler, which imparts a pleasing unity of design to the desk set and its component parts, and (2) the configuration of the letter opener in combination with the ruler and lighter, as shown.

We claim:

The ornamental design for a combination desk set and paper weight, comprising a ruler, letter opener, and cigarette lighter, as shown and described.
